J. C. KLACZYNSKI

SOUND AMPLIFIER

Filed June 6, 1922

Inventor:

John C. Klaczynski

Milano Milano attorney:

Attorney:
J. E. Hutchinson

UNITED STATES PATENT OFFICE.

JOHN C. KLACZYNSKI, OF CHICAGO, ILLINOIS.

SOUND AMPLIFIER.

Application filed June 6, 1922. Serial No. 566,256.

To all whom it may concern:

Be it known that I, JOHN C. KLACZYNSKI, a citizen of the United States, residing at Chicago, in the county of Cook and State of Illinois, have invented certain new and useful Improvements in Sound Amplifiers, of which the following is a specification, reference being had therein to the accompanying drawing.

10 My invention relates to new and useful improvements in sound amplifiers for phonographs or other musical instruments and has for its principal object the construction of the amplifier in such a manner as to give off a clear, distinct, and full tone.

15 A further object resides in the provision of means for regulating the sound to any desired pitch, said regulating being accomplished by having a plurality of sound outlets 20 let openings adapted to be opened or closed, at will, by dampers or valves.

With the above and other objects in view, which will appear as the description proceeds, my invention consists in the novel 25 details of construction and arrangement of parts, described in the following specification and illustrated in the accompanying drawings, and while I have illustrated and described the preferred embodiments of the 30 invention as they now appear to me it will be understood that such changes may be made as will fall within the scope of the appended claims.

In the drawings:

35 Fig. 1 is a top plan.

Fig. 2 is a longitudinal vertical section, and

Fig. 3 is a transverse vertical section.

40 The amplifier comprises the top 1, the sides 2 which are straight, the ends 3 which are inclined as shown, and the flat bottom 4. The top 1 is provided, over the flat bottom, with a sound inlet opening 5 over which is adapted to be secured the reproducer arm 6 of a phonograph, or other musical instrument, of well known construction. To each side of the sound inlet opening 5 I provide a sound outlet opening 7, these sound outlet openings being positioned 45 over the inclined ends 3. A perforated plate 8, preferably of screening, is secured in each of the outlet openings 7, to prevent objects from dropping into the box. The top 1 may be of a solid strip or of a plurality 50 of strips, as shown in the drawings, and when formed of a plurality of strips the

perforated plates or screening may be secured therebetween.

A depending flange 9 is secured to the underside of the top 1, around the inlet 60 opening 5, and said flange is of such a size as to engage the sides 2 but to allow for a passage between the ends 3. The inner face of this flange 9 is outwardly tapered as shown at 10 so that the bottom interior 65 diameter thereof will be greater than the top interior diameter and the outer face is downwardly tapered as shown at 11 so that the space between this flange and the inclined ends 3 will be greater at the top than at the 70 bottom. The flange 9 terminates above the bottom 4 for a purpose which will later appear. The sides 2 and ends 3 are preferably formed as a separate unit from the top 1 and will be secured to said top by 75 means of the screws 12 or other suitable fastening means. A strip of felt 13 will be inserted between the top of the sides and ends and the bottom of the top 1. This will prevent vibration due to the sound 80 waves.

Secured to the top 1, adjacent each of the outlet openings 7, is a guide-way 14 which is preferably in the form of angle iron to receive the slides 15 having the 85 knobs 16 by which they may be actuated. The slides 15 may be operated to entirely cover the outlet openings 7, to entirely uncover said openings, or to partially cover 90 the openings.

From the above it will be seen that I have provided a sound amplifier which may be positioned in a phonograph or other musical instrument in such a manner that the sounds may be emitted in an upwardly direction and that by providing the slides over the outlet openings I may regulate the pitch and throw off a clear, distinct and full tone. The sound will enter the inlet opening 6 from the reproducer arm and will be directed by the depending flange 9 towards the bottom 4. From the bottom 4 the sound will be directed or echoed to the ends 3 and then emitted through the outlet openings 7. The pitch may be regulated, 95 as previously stated, by operating the slides 15 and the outlet openings 7 may be entirely uncovered, or partially uncovered as desired. The perforated plates or screening 8 will prevent articles from being 100 dropped into the sound amplifier to in any way impair the tone. The amplifier may 105 110

be made complete as a unit for attachment to the phonograph or if desired the top 1 may be the usual top of a phonograph or similar instruments now commonly in use. 5 The density of sound may also be regulated by uncovering merely one of the outlet openings 7 or uncovering both of them. The sides, ends, and bottom of the amplifier will be constructed of such material as to 10 give off clear tones. I have found, in practice, by using an amplifier such as I have constructed that the tones are not directly emitted but instead are echoed from the bottom to the ends and then outwardly so 15 as to give off a clear, distinct and full clear tone.

Having fully described my invention what I claim as new and desire to secure by Letters Patent is:

20 1. A sound amplifier for musical instruments including a top supporting plate having a sound inlet opening and a sound outlet opening on each side thereof, a depending housing secured to the top plate, said housing having a flat bottom, straight sides 25

and inclined ends, and a depending member surrounding the sound inlet opening and extending into the housing, said depending member being spaced from the flat bottom of the housing and the ends thereof but en- 30 gaging the sides.

2. A sound amplifier for musical instruments including a top supporting plate having a sound inlet opening and a sound outlet opening on each side thereof, a depending housing secured to the top plate, said housing having a flat bottom, straight sides and inclined ends, the sound inlet opening being positioned over the flat bottom and the sound outlet openings being positioned 35 one over each of the inclined ends, and a depending member surrounding the sound inlet opening and extending into the housing, said depending member being spaced from the flat bottom of the housing and the 40 ends thereof but engaging the sides.

In testimony whereof I hereunto affix my signature.

JOHN C. KLACZYNSKI.
